DESIGN FOR A BUBBLE DEVICE

Charles H. Hagopian, New York, N. Y.

Application October 7, 1944, Serial No. 115,667

Term of patent 14 years

(Cl. D34—15)

To all whom it may concern:

Be it known that I, Charles H. Hagopian, a citizen of the United States, residing at New York city, in the county of Bronx and State of New York, have invented a new, original, and ornamental Design for a Bubble Device, of which the following is a specification, reference being had to the drawing, forming a part thereof.

In the drawing:

Fig. 1 is a top plan view of a bubble device, showing my new design.

Fig. 2 is a side elevation.

Fig. 3 is a front elevation.

Fig. 4 is a bottom plan view.

I claim:

The ornamental design for a bubble device, substantially as shown.

CHARLES H. HAGOPIAN.
